SAMPLE CLOTH DISPLAY RETAINER

Louis Cahn, Cincinnati, Ohio, assignor to The
Globe Tailoring Company, Cincinnati, Ohio, a
corporation of Ohio

Application July 15, 1938, Serial No. 219,424

5 Claims. (Cl. 206—82)

This invention relates to a cloth sample display device which will permit an inspection of substantially the entire sample body, including the marginal edges.

5 The main object of the invention is to construct a sample holder in pad or book form, with means for retaining the samples in their superimposed position, and in such a manner that upon shifting of any of the superimposed samples, the 10 underneath sample will be exposed throughout substantially its entire surface and along all of its marginal edges.

Another object of the invention is to provide 15 fastening means for the stack of superimposed cloth samples of such a character that only a minimum amount of cloth material is wasted, by being confined by the fasteners, and at the same time the samples are retained in their relative normal positions thus giving the structure a 20 neat and pleasing appearance.

Other features reside in forming an assembly 25 of the type in question sufficiently strong and durable to permit the rough usage to which such devices are submitted and at the same time providing this structure with a minimum amount of expense in manufacture.

Reference will be had to the accompanying 30 drawing forming a part of this specification and wherein like numerals of reference designate corresponding parts throughout the several views, in which—

Fig. 1 is a perspective showing the assembly.

Fig. 2 is a top plan view with one of the samples 35 pulled downwardly to expose the upper marginal edge of the adjacent following sample, and

Fig. 3 is a section on line 3—3 of Fig. 1.

The body of the assembly is formed of a single 40 sheet of suitable material such as fiber board, cardboard, laminated cloth, metal or the like. This body member includes the backing sheet 1 and the overlying top clamping section 2 which is formed by bending one end portion of the body member downwardly upon itself, thereby providing a pocket in which the filler block 3 is located. This filler block 3 occupies all of the space formed 45 between the backing sheet 1 and the top portion 2 except for a short space along the longitudinal marginal edge 4. The filler block 3 as will be noted terminates short of the marginal edge 4 to permit the sample sheets 5 to be confined under the marginal edge portion of the element 2 a sufficient distance to provide the essential neat appearance for the structure, but permitting 50 these edges to be exposed by a slight downward

movement of the samples 5 as more clearly shown in Fig. 2.

The overlying portion 2 is formed with angular ears 6 which extend beyond the marginal edge 4 and have their outer edges forming a continuation of the longitudinal marginal edge of the overlying sheet portion 2 and their inner angular edges 7 connecting the longitudinal marginal extremity of the ear 6 with the marginal edge 4 of the portion 2. Rivets or analogous fastenings 8 extend through these projecting ears 6, and through the overlying superimposed sheets 5 and the backing sheet 1, confining these parts in their proper relative position. By providing these angular extensions 6 at the bottom marginal edges 10 of the overlying portion 2 a larger portion of the sample sheets may be exposed and by limiting the extent to which these sheets project between the portions 1 and 2 a marked saving in the amount 15 of material utilized in the preparation of the samples is experienced. It will be noted that the identical shape of the ears 6 is not essential, as long as such ear portions are shaped to provide a maximum exposure of the top sample and at the same time permit sufficient surface for the proper 20 clamping of the sample sheets between the portions 1 and 2.

In structures of the conventional type and wherein the samples extend fully throughout the 25 area occupied by the filler block 3 there are two material disadvantages. First, there is the excessive waste of the cloth used in the forming 30 of the sample books or pads and second, it is impossible to expose to a prospective customer the upper marginal edge of each of the samples or any of the samples, thus making it impractical 35 to observe the upper marginal edge and by this means obtain a knowledge of the cloth formation or design, such as the squares and other markings 40 of the cloth sample.

Referring to Fig. 2, it will be noted that several 45 samples, including top sample 5' have been pulled downwardly thus exposing the upper marginal edges 5'' by arranging them in stepped relation and below the marginal edge 4 of the top portion 2 of the holder. The distortion of the top sample or any group of samples will not only expose the upper marginal edge 5'' of the samples by withdrawing them from the binder portions but will also tend to separate the vertical edge portions, as illustrated in this figure. In actual use 50 the prospective purchaser will sit in such a position that the sample container will extend transversely of his lap and will be held in the left hand with the free edges of the samples positioned 55

for the display operation by the right hand. The pulling of any one or any group of samples will automatically display the normally concealed edge 5" and also the longitudinal marginal edges thus giving the customer an opportunity to examine each and every edge of the cloth. This is accomplished, as heretofore suggested by the use of a minimum amount of material for the display book and at the same time the article produces a pleasing and desirable appearance which in itself is extremely advantageous in the presentation of fabrics.

Modifications may be made in details of construction which do not affect the inventive thought of the assembly, as for instance in the use of different types of fasteners 8, in the formation of ear extension 7, and in the shape and arrangement of the parts.

What I claim as new is:

- 20 1. In a sample device including a back panel, an end clamping portion overlying said back panel and formed with downwardly extending tabs along its marginal edges, display sheets positioned between the back panel and clamping portion, and fastening means extending through said downwardly extending marginal tabs for securing the display sheets in position.
- 25 2. In a sample device including a back panel, an end clamping portion overlying said back panel and formed with downwardly extending marginal edge portions, display sheets positioned between the back panel and marginal edge portions and extending beneath the marginal edge of said clamping portion, and fastening means extending through said marginal edge portions and back panel and securing said display sheets therebetween.
- 30 3. In a sample device including a back panel,

an end clamping portion overlying said back portion and formed with spaced downwardly extending tabs, a filler block positioned between the back panel and end clamping portion and terminating at a point spaced from the lower 5 marginal edge of the end clamping portion, display sheets positioned between the back panel and end clamping portion and abutting the filler block, and fastening means for securing the display sheets to said tabs.

4. In a sheet display device, a back panel, an upper clamping portion overlying the back panel at one end and forming a pocket therebetween, downwardly extending spaced tabs formed along the lower edge of the end clamping portion, a 15 block filling a portion of said pocket, and display sheets secured between the spaced tabs and the backing sheet and occupying at their upper edges a portion of the pocket not occupied by the filler block.

5. In a device for displaying samples of fabric, a back panel, an overlying end clamping portion, a filler block positioned between the back panel and overlying clamping portion having its lower edge spaced inward of the lower edge of 25 the overlying end clamping portion and forming a guide surface, a plurality of superimposed fabric samples secured between the back panel and overlying end clamping portion and normally engaging the guide surface of said filler block, said 30 fabric samples being so constructed and arranged as to permit their upper marginal edge to be withdrawn from beneath the overlying marginal edge of the end clamping portion, and means for fastening the sample sheets at outer spaced points 35 adjacent their edges to said backing.
